(57) **CLAIM**

The ornamental design for a adjustable weight training chair, as shown and described.

DESCRIPTION

FIG. 1 is an upper perspective view of an adjustable weight training chair showing my new design;

FIG. 2 is a side view thereof;

FIG. 3 is an opposite side view thereof;

FIG. 4 is a front view thereof;

FIG. 5 is a rear view thereof;

FIG. 6 is a top plan view thereof;

FIG. 7 is a bottom plan view thereof;

FIG. 8 is first perspective view of the adjustable weight training chair having seating pads and racks for dumbbells thereon; and,

FIG. 9 is second perspective view of the adjustable weight training chair having seating pads and racks for dumbbells thereon.

The broken lines in FIGS. 8 and 9 illustrate portions of the adjustable weight training chair that form no part of the claimed design.

1 Claim, 9 Drawing Sheets
